UNITED STATES PATENT OFFICE

MAX SADLER, OF PROVIDENCE, RHODE ISLAND, ASSIGNOR TO CAPITOL HEEL LINING COMPANY, OF PROVIDENCE, RHODE ISLAND

ARCH-SUPPORTING INSOLE

Application filed September 3, 1931. Serial No. 561,038.

This invention relates to arch-supporting insoles and has particular reference to insoles of the type commonly called "slip soles" which are used in conjunction with or as a supplement to the usual insole but are not incorporated as a permanent part of the shoe structure.

A general object of the invention is to provide an improved arch-supporting insole of the slip-sole type which is flexible and adjustable so as to offer the necessary and proper support for various kinds of abnormal foot conditions.

A further object is to provide a slip-sole of novel construction wherein a supporting pad may be readily and easily adjusted in position, and removed and replaced.

Another object is to provide a slip-sole which will effectively support the arch and other portions of the foot and at the same time will be easy and comfortable to the most sensitive foot.

A still further object is to provide an arch-supporting slip-sole which is simple in construction, easy to assemble, formed of a minimum number of parts, and inexpensive to manufacture.

These and other features of the invention will be apparent from the following description when read in conjunction with the annexed drawings and will be pointed out in the appended claims.

In the drawings:

Fig. 1 is a bottom view of the improved slip-sole.

Fig. 2 is a longitudinal section along line 2-2 of Fig. 1.

Fig. 3 is a transverse section of a shoe in which the insole is assembled, the pad being omitted, and taken along line 3-3 of Fig. 1, and

Fig. 4 is a similar transverse section with the pad in position.

As illustrated in the several figures of the drawings, the insole or slip-sole of the present invention is formed by an upper layer 2 of full shoe length and having the usual heel, shank and toe portions. The layer 2 is preferably of a single lamination of leather or leather substitute and is relatively thin

so as to give the desired flexibility and softness. To the bottom of the layer 2 is secured a flexible strip 4 of leather or similar material which extends from a point adjacent the shank forward along both sides and across 55 the toe of the insole. The marginal edges of the strip 4 are permanently attached by any suitable method, such as stitching 6, to the adjacent and overlying marginal edges of the upper layer but are entirely unconnected 60 and free from said layer along its inner edges 8 and its rear edges 10. The free inner edges of the strip 4 are spaced apart from the rear end to a point adjacent the toe tip thereby defining a central slot 12. The bottom strip 4 thus constitutes a retaining flap which cooperates with the bottom of the layer 2 to form a pocket over the entire forepart of the insole, the pocket being open at the rear end and along its longitudinal center but otherwise closed.

The pocket formed in the manner described is designed to receive and hold a supporting pad 14 which may be inserted through the rear open end and adjusted along 75 the central opening to the desired position relative to the insole as the needs of the wearer demand. The pad will be retained in its predetermined position of adjustment within the pocket by friction between the upper layer 2 on the one side and the overlapping flap 4 on the other. Obviously, the supporting pad may be entirely withdrawn and replaced with ease when desired, the central slot permitting the pad to be grasped by the fingers 80 to facilitate movement and adjustment thereof.

While it is obvious that the size, form and shape of the pad itself may be varied considerably, as may also the material of which it is made, the pad 14 is preferably made of soft rubber and is generally oval in outline. As illustrated in the drawings, the pad is of sufficient size along its widest dimension to contact with both sides of the retaining flaps and thus cannot accidentally fall out of the central slot. The pad has a maximum thickness in its center, the bottom is substantially flat, and the top gradually curved 90 from the central thick portion toward feath- 95

ered edges. A smooth curved surface, free from sharp edges, is presented by the top of the supporting pad which, together with the natural softness of the material, forms a highly comfortable support.

5 The comfort of the insole is further increased by air pockets such as 16 and 18 which form between the noncontacting surfaces of the flap 4 and the layer 2 when these members are spaced by the supporting pad and in the 10 central space between the inner edges 8 of the flap. It will thus be seen that a restricted area of the foot will be positively, albeit resiliently, supported by the pad 14 while surrounding areas will be engaged by air-cushioned portions of the insole. An efficient 15 and comfortable support for the most sensitive feet is afforded.

20 Figs. 3 and 4 illustrate the slip-sole assembled within a shoe of conventional type having an outsole 20, upper 22 and usual insole 24. The arch-supporting slip-sole of the invention fits upon the regular insole with the pocket flap 4 in contact therewith and 25 the upper layer 2 against the foot of the wearer.

20 The slip-sole is composed of a minimum number of readily assembled parts, is inexpensive to manufacture and is capable of such adjustment as to permit its use as a support for feet having widely different supporting requirements.

30 Having thus described the invention, what I claim as new and desire to secure by Letters Patent of the United States is:

35 1. An arch-supporting slip-sole comprising an upper lamination the forepart of which has the contour of a shoe insole, and a flexible strip secured to the bottom of said lamination along the marginal edge thereof only, the said flexible strip extending entirely around the forepart from points adjacent the shank, the rear and inner edges of the strip being free from the upper lamination 40 and the inner edges of the strip being spaced apart from the rear end to a point adjacent the toe tip thereby forming a central slot, the said flexible strip cooperating with the upper lamination to form a pocket having a rear 45 opening for receiving a supporting pad.

50 2. An arch-supporting slip-sole comprising an upper lamination the forepart of which has the contour of a shoe insole, a flexible strip secured to the bottom of said lamination along the marginal edge thereof only, the said flexible strip extending entirely around the forepart from points adjacent the shank, the rear and inner edges of the strip being free from the upper lamination and the 55 inner edges of the strip being spaced apart from the rear end to a point adjacent the toe tip thereby forming a central slot, the said flexible strip cooperating with the upper 60 lamination to form a pocket having a rear 65 opening for receiving a supporting pad.

opening for receiving a supporting pad, and a supporting pad within said pocket.

3. An arch-supporting slip-sole comprising an upper lamination of flexible material having a heel, shank and forepart, a flexible 70 strip secured to the bottom of said lamination along the marginal edges thereof only, the said flexible strip extending along both sides of the forepart of the upper lamination from a point adjacent the shank to the toe, the rear and inner edges of the strip being free from the upper lamination and the inner edges of the strip being spaced from each other to form a central slot, the said flexible strip cooperating with the upper 75 lamination to form a rear opening pocket, and a resilient supporting pad within the open pocket, said pad being surrounded by air pockets when the slip-sole is positioned in a shoe.

80 In testimony whereof I have hereunto set my signature.

MAX SADLER.
